US00D892328S

(12) **United States Design Patent** (10) Patent No.: **US D892,328 S**
(45) Date of Patent: **** Aug. 4, 2020**

(54) **INTRA-CARDIAC IMPLANT**

(71) Applicant: **Chengjun Guo**, Beijing (CN)

(72) Inventor: **Chengjun Guo**, Beijing (CN)

(73) Assignee: **Chengjun Guo**, Beijing (CN)

(**) Term: **15 Years**

(21) Appl. No.: **29/648,053**

(22) Filed: **May 17, 2018**

(30) **Foreign Application Priority Data**

Feb. 26, 2018 (CN) 2018 1 0158832

(51) **LOC (12) Cl.** **24-03**

(52) **U.S. Cl.**

USPC **D24/155**
